UNITED STATES PATENT OFFICE.

MORRIS MARTIN, OF MALDEN, ASSIGNOR TO JOHN C. WILSON, OF BOSTON,
MASSACHUSETTS.

KEY-CONTROLLER AND SIGNAL-TRANSMITTER.

SPECIFICATION forming part of Letters Patent No. 479,715, dated July 26, 1892.

Application filed July 16, 1889. Serial No. 317,651. (No model.)

To all whom it may concern:

Be it known that I, MORRIS MARTIN, of Malden, county of Middlesex, and State of Massachusetts, have invented an Improvement in Key-Controllers and Signal-Transmitters, of which the following description, in connection with the accompanying drawings, is a specification, like letters and figures on the drawings representing like parts.

10 My invention relates to a signaling apparatus of that kind in which automatic signal-transmitters or signal-boxes placed at various points or stations are employed to transmit messages to the main office or receiving-sta-
15 tion, which signal or message indicates the box or station from which it was sent, and may or may not include other information, as may be required. Such apparatus is in well-known use for fire-alarm or police-signaling
20 purposes, and a portion of the present invention is applicable to any signaling apparatus similar to the well-known fire and police telegraph. As the transmitters in apparatus of this kind usually have to be placed in the
25 streets or other places accessible to the public, they are commonly inclosed in boxes in order to prevent signals being sent by mischievous persons when there is no sufficient occasion for doing so. The boxes are usually
30 provided with lock and key, and in some cases have to be opened before a signal can be sent. In some apparatus, however, the transmitter is arranged to be operated by a normally-detached operating-handle that is
35 inserted from the outside of the box without opening the same, and as a check against in-
40 judicious use of the signaling apparatus by persons furnished with such operating han-
45 dles or keys the boxes are in some cases pro-
50 vided with means for trapping or retaining the operating-key when once introduced until it is released by some person who is au-
55 thorized to have means for opening the box itself. Such retaining and releasing of the
60 signal-operating key or handle has usually been accomplished wholly by mechanical means at the box, the key commonly being pre-
65 vented from turning back by a dog or obstruc-
70 tion of some kind and being released either by
75 the mechanical operation of another key and lock or by the movement of opening the box

after it has been unlocked by a suitable key other than the one that was employed for transmitting the signal and was entrapped in the act of transmitting the signal, as before 55 stated.

The detached operating device that has commonly been called, for convenience, a "key," is in reality merely a detachable crank or handle that connects more or less directly 60 with the winding arm or pull of the automatic signal-transmitter motor, and it has been probably called a "key" in describing apparatus of this kind mainly because in appearance it is more like an ordinary door-key, al- 65 though in function or effect it is more like a clock-key.

The present invention relates partly to the means for trapping or retaining a key or detachable operating-handle of this kind and 70 for releasing the same at the proper time; and this portion of the invention consists in the combination, with a key or detachable handle for operating a signal-transmitting mechanism, of a lock or detent that engages said key 75 to prevent it from being withdrawn after it has been operated to transmit a signal and an electro-magnet controlling said detent, whereby it may be operated to release the key when the said magnet is operated from the 80 main office or signal-receiving station. The said controlling-magnet is adapted to be introduced into the transmitting-circuit and is constructed to respond for the purpose of re-
leasing the key to currents differing in char- 85
acter from those commonly used for transmit-
ting the signals, being, for example, a polar-
ized magnet which while the currents are of one polarity leaves the detent in position to retain the key, but which when the polarity of 90 the current is reversed, as may be done in the main office, operates the detent in such man-
ner as to release the key, although it is ob-
vious that other changes in current besides a reversal of polarity might be employed—as, 95 for example, an increase above the normal current employed for transmitting messages. Means are provided for normally cutting the key-controlling magnet out of circuit and for introducing the same into circuit, and in prac- 100 tice it will generally be impossible to release the key until after the box has been opened

and a signal transmitted to the main office calling for a release of the key, the act of transmitting such special signal or message also introducing the key-releasing magnet 5 into circuit, so that when the proper current is applied from the main office the key will be unlocked and released.

The invention also relates to details of construction of the signal-transmitter itself, 10 which will be hereinafter pointed out.

Figure 1 is front elevation of a signal-box adapted to be operated by a detachable handle or key inserted from the outside of the box and provided with means for locking and 15 retaining and releasing said key embodying this invention; Fig. 2, a diagram representing the circuits and relation of the apparatus thereto, and Fig. 3 a detail representing a modification of the key-controlling mechanism 20 represented in Fig. 1.

The signal-box *a* may be of any suitable or usual construction containing an automatic signal-transmitter, which, so far as the key-controlling devices are concerned, may be of 25 any usual construction, as the operation of the key does not depend upon the specific construction of the transmitter. The box is shown as provided with a transmitter, the main portion of which is substantially such 30 as shown and described in application, Serial No. 275,647, filed May 31, 1888, said transmitter comprising a motor of any suitable kind, such as a spring or weight actuated train of wheelwork, a portion of which is indicated 35 at *b*, Fig. 2, that rotates a drum *c*, against the surface of which are placed a number of pairs of contact-springs *d* *d*² *d*³, &c., which pairs are connected in the main circuit, the two springs of each pair being also normally 40 connected together by shunt-circuits *e* *e*², &c., provided with circuit-breakers containing or in fact composed, mainly, of a pair of contact-springs, which normally are electrically connected, but which may be electrically separated 45 by the interposition of blocks *f* *f*², &c., of insulating material, so as to interrupt the main circuit between the corresponding pairs of springs, except when said springs are connected by making contact with a conducting 50 material on the drum *c*. The said drum is rotated beneath the pairs of contact-springs *d* *d*², &c., by the motor when the actuator for the same is wound and released, and the part of said drum co-operating with each pair of 55 springs is substantially equivalent in its operation to an ordinary break-wheel used in automatic transmission of signals, the portion of the drum which passes beneath each pair of springs being made up of alternate 60 conducting and non-conducting portions which connect or disconnect the corresponding pair of springs, such closures being variously disposed so that the breaks and closures produce on a signal-receiving apparatus 65 a message of any desired character. A suitable stop, as 100, will be employed to stop the rotation of the drum at the completion of a

revolution. It will be apparent, however, that when the shunts *e* *e*², &c., are closed the springs on the co-operating signaling-surfaces of the drum *c* can produce no effect; but if any one of said shunts is open the main circuit is brought into control of the corresponding pair of springs or contacts and signaling-surface co-operating therewith, as the circuit can then be complete only when said springs are connected by the conducting portions of the signaling-surface and is interrupted when said springs are not so connected.

The surface co-operating with each pair of springs or contacts may be of different character, so as to transmit a different message, and the shunt-circuit breakers *f* *f*², &c., are connected with operating handles or knobs *g* *g*², &c., any one of which may be pulled out 85 to break the corresponding shunt, and thus throw the main circuit into control of the corresponding pair of springs, so that when the motor is operated it transmits the message produced by said springs and the co-operating signaling-surface. The motor is operated by a crank or winding arm *h*, such as usually employed in fire-alarm or district-signaling transmitters, said arm being turned to wind the motor-actuator sufficiently to produce one 90 or more rotations of the drum *c*, according to the design of the apparatus. The said winding-arm is adapted to be operated without opening the box by means of a detachable handle *i*, similar in shape to an ordinary door-key, which may be introduced through a key-hole or opening *i*², placed in any convenient part of the box, and the bit or projecting tongue *i*³ of which key when rotated operates the winding-arm by any suitable connecting mechanism. In this instance it is shown as engaging a cam-shaped arm *k* of a lever *k*², pivoted at *k*³ and connected by a link *k*⁴ with the winding-arm *h*, so that the rotation of the key turns said winding-arm 95 sufficiently to cause the motor *b* to transmit a signal.

The parts thus far described are not herein claimed, as the operation of an automatic signal-transmitter inclosed in a box and accessible to the public, but capable of being operated by means of a detachable key or handle introduced into said box without opening the same, has been known and used prior to this invention, and the part of the transmitter thus far described is substantially the same as that shown in my application hereinbefore referred to.

In the present invention, however, the knobs *g*, *g*², &c., that operate the circuit-breakers for the shunts are so arranged as to be pushed into and retained in position to close the shunts by the door of the box when it is closed, and in order that the transmitter may send a signal when operated by the detachable handle without opening the box one pair of said springs at *d*⁵ in the normal condition of the box is not connected by a shunt, so that such pair, with the corresponding signaling-surface,

then controls the main transmitting-circuit and produces a signal, if the signaling-surfaces are rotated by the motor. This pair may, if desired, be always disconnected, except by the corresponding signaling-surface, in which case the signal of said pair will be transmitted whenever the drum is operated, and in order that the other pairs may control the main circuit during a portion of the rotation of the drum for the purpose of sending their special distinctive signals the corresponding portion of the surface of the drum that underlies the pair of springs d^5 is provided with a continuous strip c^8 of conducting material, so that during this part of the movement of the drum the main circuit is connected between the springs d^5 , and the current may then be interrupted by the breaks in the conducting-surface co-operating with any other pair of springs that then has its shunt opened by a corresponding circuit-breaker f^2 , &c. For example, the first half of the drum that passes beneath the entire series of springs may be of insulating material under all except the pair d^5 and of alternating insulating and conducting material under said pair, while the remaining half is all of conducting material under the pair d^5 and of alternating conducting and insulating material under each of the other pairs.

In order to retain the key i after it has been thus introduced and operated to transmit a signal and to subsequently release the same, the box is provided with a stop m , which prevents the key from turning wholly around, so that it can be removed from the keyhole i^2 , and a dog or detent n prevents the key from being turned back into line with the keyhole, the said dog yielding to permit the key to pass in a direction to operate the lever k^2 , and then dropping in behind the key-bit, as shown in Fig. 3, and in order to release the key the said dog must be removed from the path of the key-bit, so as to permit the key to be turned back. In apparatus of this kind in which the key has been retained by a pawl or detent the said pawl has commonly been operated mechanically and automatically to release the key, either by another key introduced at some other part of the box, or by the movement of some part produced by moving the door of the box itself.

In the present invention the release of the key is effected by electrical appliances and is controlled from the main office or station at which the signals transmitted from the box are received. This result is effected by means of an electro-magnet o (shown in Fig. 1 as a polarized magnet and in Fig. 3 as a neutral magnet) and armature o^2 therefor, co-operating with said dog n in such manner that when the armature is in the position shown in full lines the dog is permitted to remain in position to engage the key and retain the same in the box; but when said armature is moved to the dotted-line position it removes the dog from the path of the key-bit, so that the key

may be turned back and removed from the keyhole. The magnet o is shown as constructed or adjusted so as not to operate the dog n when affected by the currents normally used for transmitting, but is operated by an abnormal current, which may be applied from the main office.

When the polarized magnet is used as shown in Fig. 1, it is so arranged that the currents of the polarity normally used for transmitting retain the armature in the full-line position, and in order to operate the said armature to release the key the polarity of the current is reversed by any suitable pole-changing instrument—such, for example, as represented at P , Fig. 2—the said instrument being of a well-known character and requiring no specific description, it operating when turned upon its pivot p to reverse the connection of the battery-poles B , with the main line 2 3 4 extending from the main or signal-receiving station to the box or transmitting-station.

The signal-receiving instrument at the receiving-station is not shown, as it may be of any well-known form of receiving-instrument—such, for example, as a self-starting register—either included in the main circuit or in a local circuit controlled by a relay in the main circuit.

In the construction shown in Fig. 3 the armature o^2 is normally at a considerable distance from the pole of the magnet o , so as not to be attracted by currents of normal strength; but it may be attracted by increasing the current, which may be done by throwing on additional battery by a suitable key or switch at the main office. As there are usually several of the transmitters on a single circuit and it is not desirable to have much resistance in said circuit, the magnet o is preferably normally cut out from the main circuit by means of a shunt 5 6, which may be opened by an authorized person having access to the inside of the box a , said shunt being shown in this instance as controlled by the same circuit-breaker f and knob or handle g as the shunt e for the pair of springs d , which are employed to transmit the message to the main office that is understood as a call, for applying the proper current from said office to release the key. After a signal has been sent by the operation of the key i the said key is retained in the box until the arrival of the proper officer, who may obtain the release of the key by pulling out the knob g and transmitting the corresponding signal, which is recognized as the "key-release" signal, upon receipt of which the receiving-station attendant operates the key P , thus causing the magnet o to effect the release of the key, the said magnet o having been introduced into the main circuit by opening the shunt 5 6 in the same operation that the shunt e was opened for transmitting the key-release message. If desired, the receiving-station operator might set the switch p at any time in position to connect the battery properly for the release

of the key, so that the key would be released immediately upon opening the shunt 5 6 and bringing the magnet into the main circuit; but by the herein-described means the receiving-station attendant always has it in his power to know when a key is released and in fact at all times controls the release of the key.

I claim—

- 10 1. A signal-box and signal-transmitter inclosed therein connected in circuit with a central office, said box being provided with an opening to receive a detachable handle or key for operating said signal-transmitter, combined with a detent that engages said key when introduced into the box, and an electro-magnet that operates the said detent, and a circuit-changer at the central office for operating said electro-magnet, substantially as described.
- 15 2. The combination of a box and signal transmitter inclosed therein adapted to be operated by a detachable handle or key introduced from the outside of the box without opening the same, a detent for retaining said key, and an electro-magnet for operating said detent included in the transmitting-circuit of the box, and a normally-closed shunt for said magnet and circuit-breaker therein, substantially as described.
- 20 3. A signal-box containing a signal-transmitter composed of a motor and a number of signaling-surfaces operated simultaneously thereby, said motor being adapted to be operated by a detachable handle introduced without opening the box, combined with a detent for said detachable handle, an electro-magnet included in the transmitting-circuit for operating the said detent, a shunt around said magnet, and circuit-breaker in said shunt operatively connected with the controlling mechanism for one of the signaling-surfaces of the transmitter, as set forth, whereby said shunt is broken when one only of said signaling-surfaces is placed in control of the transmitting-circuit, substantially as described.

4. A signal-transmitting instrument comprising a number of distinct signaling-surfaces connected to move simultaneously and contacts controlled by said surfaces connected in series with one another in the transmitting-circuit, combined with shunt-circuits connecting the co-operating contacts for all of said surfaces but one, which one pair of contacts is normally disconnected except at the 50 co-operating signaling-surface, and an independent circuit-breaker in each of said shunts, substantially as and for the purpose described.

5. In an electric circuit, a multiple-signal 60 transmitter comprising two signaling-surfaces and contacts or breakers co-operating therewith, one of which is normally in said circuit and the other of which is normally shunted out, a movable part or member for opening 65 and closing said shunt, and automatic mechanism for moving said signaling-surfaces, substantially as described.

6. In an electric circuit, a multiple-signal transmitter comprising three signaling-surfaces 70 and contacts or breakers co-operating therewith, one of which is normally in said circuit and each of the others normally shunted out, and two independently-movable parts or members, one for opening and the other 75 for closing each said shunts, substantially as described.

7. In a signal-box, the combination, with a case and door, of a multiple-signal transmitter having several horizontally-sliding independent controlling devices therefor adapted to be drawn out by hand and returned to their normal position by being struck by the door as it is closed, substantially as described.

In testimony whereof I have signed my 85 name to this specification in the presence of two subscribing witnesses.

MORRIS MARTIN.
